GAS BURNER

David L. Painter, Evanston, Ill., assignor to Surface Combustion Corporation, Toledo, Ohio, a corporation of Ohio

Application April 7, 1951, Serial No. 14,752

Term of patent 14 years

(Cl. D81—1)

To all whom it may concern:

Be it known that I, David L. Painter, a citizen of the United States, residing at Evanston, State of Illinois, have invented a new, original, and ornamental Design for a Gas Burner of which the following is a specification, reference being had to the accompanying drawing, forming a part hereof.

Fig. 1 is a perspective view of a gas burner embodying the present invention and adapted for use with ordinary house-heating furnaces.

Fig. 2 is an end view of Fig. 1.

Fig. 3 is a side elevation of Fig. 1.

The dominant features of my design reside in the portions shown in full lines.

I claim:

The ornamental design for a gas burner, as shown and described.

DAVID L. PAINTER.
